UNITED STATES PATENT OFFICE.

ANDREW M. VANDERBEEK, OF PLAINFIELD, NEW JERSEY.

METALLIC DISH-RACK.

1,241,169.

Specification of Letters Patent. Patented Sept. 25, 1917.

Application filed September 30, 1915. Serial No. 53,340.

To all whom it may concern:

Be it known that I, ANDREW M. VANDERBEEK, a citizen of the United States, and a resident of the city of Plainfield, county of 5 Somerset, and State of New Jersey, whose post-office address is Plainfield, N. J., have invented a new and useful Improvement in Metallic Dish-Racks, of which the following is a specification.

- 10 The object of my invention is to provide a device of this class which may be used with white enamel sinks and protect the same, and yet the rack will remain clean and sanitary and durable under all the conditions 15 of service. A further object is to provide a rack which is free from places where dirt may accumulate and which is thoroughly braced so as to prevent all distortion under the normal conditions of service. A further 20 object is to provide a rack which may be used as a dish support or table protector or other device for supporting one body away from another.

For a more particular description of my 25 invention, reference is to be had to the accompanying drawing, forming a part hereof, in which—

Figure 1 is a plan view of my improved rack.

30 Fig. 2 is a side elevation of the same.

Figs. 3 and 4 show an improved form of rubber shoe for supporting the rack, Fig. 3 being a plan view and Fig. 4 a side elevation.

35 Figs. 5 and 6 show one of these improved shoes on a foot projecting from the rack, Fig. 5 being a plan view and Fig. 6 a sectional view, the section being taken through the shoe.

40 Throughout the various views of the drawings, similar reference characters designate similar parts.

In the preferred embodiment of my invention an endless loop which is connected 45 near its middle by a transversely extending bar 2 to stiffen the same and its ends are connected by the longitudinally extending bars 3 and 4, the bars 3 having loops 5 at intervals, say two intervals, and the bars 4

being straight from end to end. Both the 50 bars 3 and 4 are welded and preferably electrically welded to the frame 1, as well as the crossing 2 so that an exceedingly rigid structure is formed without recesses for the accumulation of dirt. 55

Each foot 5 carries a rubber shoe 6 which is made substantially as shown in Fig. 3 to Fig. 6 inclusive, with an elliptical cross-section and a rectangular longitudinal section with an opening 7 at the bottom through 60 which water may drain. This shoe 6 is somewhat elastic so that it is enlarged when passing over the foot 5 to which it is attached and is held in place by its resiliency. As these rubber shoes or tips become worn they 65 may be readily removed and replaced so that they are always available in a proper condition to support the rack.

The rack may be used, as above stated, by being placed in a sink so as to keep the dishes 70 off the same while they drip, or it may be placed on a table or other piece of furniture so as to carry a hot iron or other heated object, or it may be used on a shelf, or otherwise, and cake placed thereon to dry so as 75 not to become soggy. It is capable of a variety of uses not all of which have been set forth in the foregoing.

While I have shown and described one embodiment of my invention, it is obvious 80 that it is not restricted thereto, but is broad enough to cover all structures that come within the scope of the annexed claims.

Having thus described my invention, what I claim is,

1. In a device of the class described, an 85 endless loop having a transverse bar and longitudinal bars all welded together, some of said longitudinal bars being provided with loops to form feet.

2. In a device of the class described, a 90 rubber shoe having a perforated bottom and a longitudinally disposed opening adapted to pass over the foot of a rack.

ANDREW M. VANDERBEEK.
